WINDOW FLY SCREEN

Application filed August 12, 1927. Serial No. 212,442.

The present invention relates to improvements in window screens adapted to prevent insects and the like from entering through the open window of a building.

5 An important object of the invention is to provide a window screen arranged so that the window opening will be covered by a strip of screening material automatically upon the operation of the window sash.

10 A further object of the invention is the provision of a screen which will be operated simultaneously with the sash so that the possibility of having an uncovered opening in the frame of a window will be eliminated.

15 A further object of the invention is to provide a window screen which will be snugly fitted in the frame of the window to prevent the passage of insects between the screen and the frame structure of the window.

20 A still further object of the invention is to provide a window screen which will be automatically operated to window closing position by the movement of the window sash and will be automatically rolled upon the 25 roller when not in use.

Another object of the invention is the provision of a window screen of the above character which is relatively simple and durable of construction and which can be sold at a 30 comparatively low cost.

Other objects and advantages of the invention will become apparent as the description progresses.

In the accompanying drawing forming 35 part of this specification and in which like reference characters are employed to designate corresponding parts throughout the same:

Figure 1 is a front elevational view of a 40 window with the bottom sash in elevated position showing my improved screen operatively associated therewith;

Figure 2 is a similar view showing the upper sash partly lowered and the screen attached thereto while the lower screen is detached from the lower sash;

Figure 3 is an enlarged transverse sectional view taken on the line 3—3 of Figure 2;

Figure 4 is a similar view taken on the line 50 4—4 of Figure 1;

Figure 5 is a horizontal view taken on the line 5—5 of Figure 1, and

Figure 6 is an enlarged transverse sectional view taken through the bottom rail of the bottom window sash.

Referring to the drawing, wherein for the purpose of illustration is shown the preferred embodiment of my invention, the numeral 10 designates a window frame embodying vertical side rails 11, a head rail 12 and a bottom horizontal sill 13. As shown to advantage in Figure 3, the sill 13 is formed with a longitudinally extending slot 14 adjacent its inner edge.

Mounted for vertical sliding movement in the frame 10 is an upper sash 15 and a lower sash 16 slidably fitted in suitable grooves formed in the inner sides of the frame. Each sash embodies a marginal frame and a window pane fitted within the said frame. The longitudinal centres of the bottom rail of the lower sash and the top rail of the upper sash respectively, are formed with vertically extending recesses or bores 17, these bores intersecting a horizontally extending bore which extends from the inner sides of the sash frames adaptable to receive removable locking pins 18. With reference to Figure 6, it will be noted that the pins 18 embody straight longitudinal shanks slidably engagable with the bores.

As shown to advantage in Figure 2, the upper extremities of the main frame and side rails 11 are provided with angular recesses in which are secured transversely opposed roller brackets 19, one of the brackets being preferably formed with a circular pintle receiving opening while the opposite bracket is formed with a non-circular opening adapted to receive a pintle of elongated cross section so as to support a roller 20.

The roller 20 is constructed so as to normally rotate in one direction tending to wind thereon a foraminous screen 21, in the nature of a shade roller.

An elongated strip of flexible screening material 21 is attached to the roller 20, one edge being disconnected for connection with the window sash 15. The free edge of the screen 21 is connected with the longitudinal

inner edge of an attaching strip 22 formed so as to be freely movable in the sash grooves of the window frame and adapted to be detachably connected to the upper edge of the upper sash. A bracket 23 is fixed to the centre of the attaching strip 22, this bracket including an ear which extends vertically from the centre of the strip and is adapted to engage the recess 17 formed in the sash rail.

10 A similar structure is provided at the bottom of the window frame, a transversely elongated box-like casing 24 being formed below the sill to receive the roller and screen rolled thereon. As clearly illustrated in Figure 5, the side rails 11 of the window frame are formed with inwardly cut grooves 25 in which the longitudinal side edges of the screen are reciprocated. The lower screen is 20 also connected with a strip 22 arranged for detachable connection with the lower edge of the lower window sash for intermittent connection with the sash. Referring in particular to Fig. 6 it should be noticed that the outer longitudinal edge of the attaching strip 22 is forced upwards against the bottom of the sash 16, due to the strip 22 pivoting about the ear of the bracket 23 and pin 18 as an axis, this pivoting being accomplished by the 30 weight of the screen material, which is attached to the inner edge of the strip. In this manner the opening between the strip 22 and sash 16 is closed.

35 In use, the free edges of the upper or lower screens 21 may be securely connected with the corresponding edges of the window sash, by inserting the ear of the bracket 23 of the connecting strip in the recess formed in the sash and slidably inserting the pin 18 to lock 40 the ear in position. When the upper sash is lowered, the screen will be pulled downwardly so as to cover the window opening and prevent the entrance of insects. Similarly, elevation of the lower sash will lift the 45 lower screen and cover the lower window opening. Furthermore, during the colder seasons of the year the screens 21 can be disconnected from the sashes and will be retained in rolled position at the upper and 50 lower portions of the window frame so as to be well protected from the elements. During the warmer seasons, when insects are prevalent, the connecting strips 22 are attached to the rails of the sashes as previously indicated so that slidable operation of the sashes will automatically cause the screens to cover the opened portions of the window 55 and prevent the entrance of insects.

60 This construction obviates the necessity of removing screen frames which may be attached to the window frame at different seasons of the year and maintaining a storage space for the same. Furthermore, my improved screens will only be exposed when the 65

window is opened so that the life of the screen will be greatly prolonged.

It is to be understood that the form of my invention herein shown and described is to be taken as a preferred example of the same, and that various changes as to the shape, size, and arrangement of parts may be resorted to without departing from the spirit of the invention or the scope of the subjoined claims.

Having thus described my invention, I claim:

1. The combination with a lower window sash having a bottom rail formed at its longitudinal center with a vertically extending recess intersecting a horizontally extending bore provided with locking pins, of an attaching strip of slightly less width than said rail, a bracket fixed to the center thereof, and having an ear extending into the said vertically extending recess, said ear being slightly longer than the depth of said recess, and engaged by the locking pin, and screen material attached to the inner longitudinal edge of the attaching strip, so that the weight of the screen material pivots the strip to cause the outer longitudinal edge to engage against the bottom of the bottom rail.

2. The combination with the lower sash of a window frame having a recess in the bottom thereof and a bore in the side communicative with said recess, of an attaching strip disposed below said sash, said strip being adapted to turn slightly in the frame, a bracket comprising an eye on said strip adapted to fit into said recess, the eye portion of said bracket being slightly longer than the depth of said recess, a bolt disposed through said bore into said recess and engaging said eye, said attaching strip being free to be pivoted relative to said sash, and a screen attached to the inner edge of said attaching strip adapted by virtue of its weight to hold said attaching strip at an inward and downward inclination to said sash for causing the outer edge of said strip to engage said sash to close the gap therebetween.

In testimony whereof I have affixed my signature.

ADOLPHE BRIÈRE.
